US0D1008450S

(12) **United States Design Patent** (10) **Patent No.:** **US D1,008,450 S**
(45) **Date of Patent:** **** Dec. 19, 2023**

(54) **MASK**

(71) Applicant: **KEC-TECH LTD**, Shenzhen (CN)

(72) Inventor: **Shixiong Wang**, Shenzhen (CN)

(73) Assignee: **KEC-TECH LTD**, Shenzhen (CN)

(**) Term: **15 Years**

(21) Appl. No.: **29/780,537**

(22) Filed: **Apr. 26, 2021**

(51) **LOC (14) Cl.** **29-02**

(52) **U.S. Cl.**

USPC **D24/110.1**

(58) **Field of Classification Search**

USPC D24/110, 110.1–110.6, 127, 128, 162, D24/164; D16/339; D29/108, 110, 111

Assistant Examiner — Amanda J Berlinski

(74) *Attorney, Agent, or Firm* — Culpepper IP, LLLC; Kerry S. Culpepper

(57) **CLAIM**

The ornamental design for a mask, as shown and described.

DESCRIPTION

FIG. 1 is a perspective view of a mask showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view of the mask thereof where the mask is in a configuration of use.

The broken lines in the drawings depict portions of the mask that form no part of the claimed design.

1 Claim, 9 Drawing Sheets
